BOAT HOIST CAM PLATE

Everett A. Johnson, 15 S. Prospect Ave.,
Park Ridge, Ill. 60068

Filed Jan. 2, 1973, Ser. No. 319,983

Term of patent 14 years

Int. Cl. D12—05

U.S. Cl. D12—60

FIG. 3

FIG. 1

FIG. 4

FIG. 5

FIG. 2

FIG. 1 is a face view of a boat hoist cam plate embodying my new design.

FIG. 2 is a rear view of the boat hoist cam plate shown in FIG. 1.

FIG. 3 is a top edge view of the boat hoist cam plate shown in FIG. 1.

FIG. 4 is a section through the boat hoist cam plate taken at 4—4 in FIG. 1.

FIG. 5 is a section taken through the boat hoist cam plate viewed at 5—5 in FIG. 1.

The broken line showing of lever arm and clevis ring illustrate the environment.

I claim:

The ornamental design for a boat hoist cam plate, as shown and described.
